CLAIM

The ornamental design for an air redirector mount, as shown and described.

DESCRIPTION

FIG. 1 is a perspective view of an air redirector mount, according to a first embodiment, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of the air redirector mount, according to a second embodiment showing my new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken line showing of an air redirector mount is for the purpose of illustrating portions of the article and form no part of the claimed design.
